UNITED STATES PATENT OFFICE.

EDWARD P. BAIRD, OF EVANSTON, ILLINOIS, ASSIGNOR TO BAIRD MANUFACTURING COMPANY, OF CHICAGO, ILLINOIS, A CORPORATION.

TELEPHONE TOLL APPARATUS.

No. 880,708.

Specification of Letters Patent.

Patented March 3, 1908.

Application filed March 25, 1901. Serial No. 52,678.

To all whom it may concern:

Be it known that I, EDWARD P. BAIRD, a resident of the city of Evanston, in the county of Cook, State of Illinois, have invented certain new and useful Improvements in Telephone Toll Apparatus, of which the following is a full, clear, and exact description.

The present invention relates more particularly to telephone lines and toll-collecting and receiving devices associated therewith.

It has heretofore been proposed to employ apparatus which required deposit of a coin before the line signal at the central exchange became operative, or could be actuated. The purpose thereof was to avoid the necessity of having the central operator answer a call until payment had been made, or to avoid the necessity of having the central operator wait while the subscriber deposited a coin. In such devices, means were provided for refunding the deposited coin in event the connection desired by the depositor could not be made, *e. g.*, when the station called for was "busy."

To retain the coin in position so it could, if necessary, be re-refunded, means were provided, whereby the coin was temporarily held. In these devices some operation of the central operator, or the depositor was necessary to effect such displacement of the coin into the coin-drawer, *e. g.*, the central operator was obliged to send generator or high-voltage current over the line, or the depositor was required to operate a push-button or place the telephone on the switchhook. In practice, the operation to effect said displacement would sometimes be neglected, and the delays in the service resulting from this operation have been objectionable.

One object of the present invention is to provide an improved telephone toll-line and apparatus wherein displacement of a deposited coin into the coin drawer is not dependent upon either the central operator or the depositor, and thus to avoid the objections to apparatus heretofore employed.

Another object of the invention is to provide improved apparatus whereby the line-signal at central station, upon deposit of a coin into the toll-receiver, will become operative, and whereby said signal will remain actuated or operative until the call is responded to by the central operator.

Another object of the invention is to provide an improved toll apparatus by which the coin-controlled line-signal at the exchange will be caused to remain operative until a call is responded to by the exchange-operator, independently of the coin deposited for the call and which causes the operation of the line signal.

Another object of the invention is to provide improved means whereby the signal circuit wherein the line relay is located, is broken at subscriber's station to electrically disconnect the grounded and other contacts at the toll receiver from the telephone-line as soon as the central operator responds to a call by inserting a plug into the switchboard.

The invention still further designs to provide an improved toll-receiver wherein the deposited coin is positively shifted to effect the actuation of the signal which notifies the central operator that a connection is desired.

Still another object of the invention is to provide a toll apparatus in which a coin must be deposited before the central office can be signaled, with a device for producing an audible signal, the actuation whereof is deferred until the central operator responds to a call so as to insure the receipt of the audible signal by the central operator.

The invention consists in the several novel features hereinafter set forth, and more particularly defined by claim at the conclusion hereof.

In the drawings Figure 1 is a diagrammatic view of a telephone system and toll-apparatus embodying the several features of the invention. Fig. 2 is a view of the improved toll-receiver, such being shown in vertical section taken on line 2—2 of Fig. 3. Fig. 3 is a plan of the toll-receiver, the inclosing case being shown in section. Fig. 4 is a view in side elevation, the case being omitted. Fig. 5 is a view in vertical transverse section taken on line 5—5 of Fig. 4. Fig. 6 is a detail view in horizontal section of the coin-carrier. Fig. 7 is a detail view in side elevation showing the mechanism for producing the audible signal.

The toll-receiver (shown more fully in Figs. 2-7) is located at the subscriber's station, and comprises a suitable inclosing case 6, usually formed with a cover-plate 7 for convenience in examining and assembling the inclosed parts. The case is provided

with a coin-receiving slot 8, a cup 9 for catching the rejected and refunded coins, and a coin-drawer 10 secured in the case by a lock 11.

The operating parts of the toll-receiver are sustained in relative position in and by a frame comprising sides 12 and 13, secured together and to the case in any suitable and convenient manner. A coin-carrier A is pivotally sustained by and revolvably held by a shaft 14 journaled in the frame sides and having a polygonal portion extending through a correspondingly-shaped sleeve 15 secured in wings 16 of the coin-carrier. The carrier comprises suitable walls, between which a coin-guide or channel 17 is formed. The front or upper end of the coin-channel 17 is located immediately beneath coin-receiving slot 8, and into said channel deposited coins will fall. A stop 18 is located in the coin-channel of the carrier, holds a deposited coin of proper size adjacent the upper or front end and in position to cause the coin to cause the actuation of a signal device. The bottom or lower wall of coin-channel 17 is notched or slotted as at 19 to expose a portion of a coin held in the carrier, and permit the coin to engage and shift mechanism hereinafter described, when the carrier with a coin therein, is shifted. Shaft 14 is journaled in sides 12 and 13 of the frame, extends through one of the side-walls of the inclosing case, and has secured to its projecting terminal an operating-arm or crank 20, whereby the shaft and coin-carrier may be manually shifted. A coil spring 21 holds the carrier in normal position against a stop 22 and restores the carrier after operation. Wings 16 on the coin-carrier, obstruct the coin-receiving slot 8 while the carrier is out of normal position and prevent a coin from being inserted except when the coin-channel 17 is immediately beneath coin-receiving slot 8 in position to receive a deposited coin.

Coin-channel 17 is extended entirely through the carrier, so a coin insufficient in diameter to engage stop 18 (see Fig. 6) will pass out of the carrier at its lower end, and into an inclined run-way or guide 23 located in back of the carrier, thence down an inclined guide 24 at the side of the frame, thence through a slot or opening 25, over an inclined wall 26, through an exit-opening 27 in the front of the case and into cup 9 and within reach of the depositor. If, through inadvertence, a smaller coin than that wherefor the collector or carrier is designed, or a slug, be deposited, it will not render the collector operative to produce a signal, but will be rejected and returned to the depositor.

An arm B sustained by a shaft 25 journaled in the sides 12 and 13 of the frame, extends normally into the path of movement of a coin in the carrier. Arm B is engaged and shifted by a coin in the carrier during the manually-imparted oscillatory shift of the

carrier. At one side of the frame a switch-arm C formed of non-conducting material, and contact-strip c, is arranged normally in position to engage a contact-spring 29. Arm B is yieldingly held in normal position against a cross-rod 30, and is restored to such position by a spring 31. An electro-magnet D is secured in the frame in convenient manner and comprises a helix 32. A pivoted armature 33 is operated by the magnet, and a spring 34 holds the armature normally away from the magnet. Electro-magnet D is responsive to current employed for speech-transmission over the telephone line, that is, the helix will be energized and the armature will be operated when current for speech-transmission passes through the helix. Arm B is provided with a part 35 arranged to be engaged by a hook 33' operated by armature 33 when said arm has been shifted by a coin and the armature retains arm B and switch-arm C in position to cause contact c to engage contact-spring 29 and also contact springs 36 and 37 (see dotted lines, Fig. 4), which are secured by screws and a block 38 of insulating material, to the frame-side 12. After the arm B has been shifted and is held by the armature-hook, the switch-arm C and said arm remain held thereby until helix 32 is energized (by means presently described). The purpose in providing such mechanism is to signal the central office that a coin has been deposited, and further, to continue such signal until the central operator has responded to the call.

A striker-lever m is also carried by shaft 25, at one side of the frame. Lever m is arranged to engage a bell or gong M to produce an audible signal which will notify the central operator that a coin has been deposited. When the carrier with a coin therein is shifted, shaft 25,—which simultaneously shifts switch-arm C—will be shifted and held in shifted position by armature-hook 33' until helix 32 is energized, and such operation will cause striker-lever m to be shifted and held away from bell M until the shaft 25 is released, when the striker-lever impelled by spring 31 will engage the bell and produce an audible signal. In practice, it has been found that in some instances, persons have actuated signals which could be actuated by a current of electricity in fraudulent manner, by "bridging" the circuit at exposed portions of the conductors or by "grounding" the current. The audible signal produced by bell M is therefore employed to confirm the indicator signal at the central office, which is controlled by switch-arm C. The actuation of bell M is deferred by armature-hook 33', and by means hereinafter defined, until the operator has answered the call, and it will be understood that the audible-signal device is not actuated until connection between the subscriber's station and the ex-

change for speech-transmission has been made.

A dog 39 provided with ratchet-teeth is pivotally sustained by cross-rod 30, arranged in the path of movement of a coin in carrier A, engages the edge of the coin and prevents retraction of the coin and carrier and repeated operation of the arm B by the same coin. Said dog is held in proper normal position against a stop 40 and restored thereto by a spring 41. In operation the coin successively engages the teeth of the dog, and is prevented from being retracted until the coin has been discharged from the carrier. When a coin is shifted by the carrier, and the coin has passed beneath arm B and dog 39, the coin will be discharged from the carrier and will fall into a movable coin-distributer E, being directed thereto by cross-walls 42 and 43. Beneath the coin-distributer, a stop 44 is formed, whereon the coin, after discharge from the carrier, will rest. Thus it will be seen that each deposited coin of proper size will be shifted by the carrier to cause the actuation of a signal, then discharged into the movable distributer E, and will be held therein (until removed by mechanism hereinafter described), by stop 44. In back of stop 44 a guide 45 is formed, which directs coins, when the coin-chute E is moved backwardly, into coin-drawer 10. In front of said stop, guide or run-way 26 is formed, which directs coins which fall thereon (when the distributer is shifted forwardly), into cup 9 at the outside of the case. A gate 46 pivotally sustained as at 47, prevents insertion of a wire or tool through opening 27 for fraudulent purposes.

In practice, it has been found desirable to require the deposit of a coin at the subscriber's station before the line-signal at the central office can be actuated. In event the desired service or connection cannot be given, the coin must be refunded. If the desired connection is made, the coin should eventually be placed in the coin-drawer.

The movable distributer E is secured by pendant e' to an armature e pivotally sustained as at 49 in a frame 50. Armature e has an extension 51 to which is secured an arm 52 extending into the path of movement of a coin held in carrier A, and said arm is arranged to be engaged by the coin during the initial part of its travel. On each shift of the carrier with a deposited coin therein, the coin will at the outset, engage arm 52, rock armature e about its pivot and shift the distributer E backwardly to discharge a previously deposited coin (if any there be), from the chute and into the coin-drawer.

An electro-magnet G, when energized (by means at the central office) attracts armature e and shifts the distributer E forwardly, which causes a deposited coin to fall

in front of stop 44, and to be refunded to the depositor. A centralizing-spring 53 retains the distributer normally in position above stop 44 and restores the armature and distributer after shift in either direction. Binding-posts 54 are provided for the conductors, connecting the toll-receiver and telephone-line. The coin carrier serves as means for shifting a coin to operate the line signal switch, the distributer to displace a coin into the coin receptacle and to set the audible-signal device so it will be operative when the exchange operator answers the call.

Referring to Fig. 1, H designates a subscriber's station, I a switchboard located at a central exchange K, and J is a connecting telephone line comprising branches 55 and 56. These branches are connected to line-springs i and i' of switchboard I at the central exchange and to the usual parts at the subscriber's station which includes a transmitter, induction coils, receiver, signal-bell and switch-hook 57, connected together in usual manner, as well understood in the art. The switchboard shown is of the type commonly known as a "relay-board." A line-relay 58 is associated with each subscriber's line and is included in a signal circuit comprising branch 55 of the line, switch 77^a, and wires 77 and 77^b extending to battery 75 and ground at 82. When energized the line relay causes the actuation of a visual signal 79 such as a lamp in a local circuit. A cut-off relay 59, included in a circuit which extends from ground at 82, conductor 81 and terminating in a test-ring 60, excludes the line-relay and visual signal or indicator from the signal circuit when the operator inserts a plug in the spring-jack. A cord-circuit L including plugs 61 and 62, a battery 63 and other usual parts and signals, is provided at the central exchange. A generator 64 grounded as at 65 and connected to a switch 66, is included in the cord-circuit, and thereby a generator current (usually of 110 volts) may be impressed upon the telephone-line.

At the subscriber's station, a branch wire 67 connects branch 55 of the telephone-line with contact-spring 37 in the toll-receiver, and electro-magnet D is included in a branch conductor 68 leading from branch 56 of the telephone-line to contact 36 of the toll-receiver. Contact-spring 29 is connected by wire 69' to ground as at 69. A conductor 70 connects a contact 71 arranged to be engaged by switch-hook 57 only when the receiver has been removed from the hook, and the helix of electro-magnet G, and is connected to ground as at 72. Magnet G is wound to respond to generator current from generator 64 (usually one hundred and ten volts), greater than the current (usually twenty-four volts) sent over the line by 130

- battery 63 for talking purposes. As a result, magnet G will not be energized by current from battery 63, but only when current from generator 64 is impressed upon the line.
- 5 When the subscriber's station is out of use, the electro-magnet will be disconnected from the line at switch-hook 57 and contact 71.
- The operation will be as follows: To signal the central exchange, the subscriber inserts 10 a coin of proper denomination and size through coin-receiving slot 8 (see Fig. 2), into coin-carrier A. The depositor then shifts operating-arm 20 forwardly, and such movement will cause the carrier and deposited coin to move positively downward.
- 15 During its descent, the coin will first engage arm 52 of pivoted armature e, shift said arm forwardly, thus causing distributor E to travel backwardly and displace the coin (if 20 any previously deposited in payment for prior service or connection is therein), from stop 44 and into the coin-drawer. The armature e and distributor E will be promptly restored to normal position by spring 53.
- 25 Descending further, the coin will engage dog 39 and retraction of the coin will be thereby prevented. The coin will simultaneously engage and shift arm B until its lower end has passed beyond the hook of armature 33.
- 30 After the coin clears the arm B and dog 39, it will fall from channel 17 of the carrier, between walls 42 and 43, and into the distributor where it will rest on stop 44 as shown by dotted lines in Fig. 5. After engagement with a coin, arm B will be locked 35 and held by armature 33 until electro-magnet D is energized. When arm B is thus locked, switch-arm C will be in position shown by dotted lines in Fig. 4, and conductor plate will electrically connect contacts 29, 36 and 37, each with the other, and striker-lever m will also be held in retracted position. With the parts in such position, the line-relay 59 will immediately become operative 40 to notify the central operator of the deposit of a proper coin in the toll-receiver, because current will flow from battery 75 (which is grounded at 82) over conductor 77, through line-relay 58 (energizing said relay and closing 45 the local signal circuit wherein visual signal 59 is located), thence through the armature 77^a of cut-out relay 59, over branch wire 55 of the telephone-line, thence by conductor 67, contact 37, contact c of switch-arm C, and contact 29 to ground at 69. Visual signal 79 will thus notify the central operator that a connection is desired and that payment has been made for the desired service. Such signal continues until 50 60 the central operator responds by inserting a plug of the cord-circuit L, into the spring-jack of the switchboard I. When the central operator inserts a plug into the switchboard, current will pass from battery 63 of the cord-circuit, over the conductor leading

to and by the tip of one of the plugs, thence by contact-spring i of the spring-jack, branch wire 55 of the telephone-line, conductor 67, contact spring 37, contact c of switch-arm C, contact 36, electro-magnet D, — 70 energizing the helix of said magnet and operating armature 32 to release arm B, — and thence by conductor 68, branch wire 56, contact spring i' of the spring-jack, contact ring 80 of one of the switch-plugs, and thence by 75 usual connections to battery 63. When electro-magnet D has been energized, the signal circuit will be broken at the toll-receiver and the grounded wire 69 will be disconnected from the line, thus rendering 80 the line relay at the exchange inoperative until another coin has been deposited. Simultaneously, current will flow from battery 63 through the larger ring of the inserted plug, test-ring 60 and wire 81, and 85 cut-out relay 59 to ground at 82. The cut-out relay will then be energized, attract its armature, and thus break the circuit of the line-relay 58 and the local signal circuit in which lamp 79 is included. 90

Upon release of arm B, — which occurs when electro-magnet 32 is energized, and the central operator has inserted one of the plugs of the cord-circuit into the spring-jack, and communication has been established between the central operator and the subscriber's station over the telephone circuit, — 95 striker-lever m will be released and actuate bell M, thus producing an audible signal which will be transmitted over the line to the central operator. This audible signal confirms the operation of the line signal at the exchange, and thereby the operator will be informed of the deposit of a coin. If the confirmatory audible signal is not heard, the operator will know that the line-signal has been actuated by other means than a deposited coin. For example, if attempt should be made to actuate the line-relay by connecting conductor 67 with ground or with 100 one of the binding-posts connected with ground, or the line should be connected with ground in any other manner, the audible signal device will not be actuated, and the operator will know that payment has not been 105 made. It will thus be seen that the indicator at the central office is immediately actuated, upon the deposit of a coin, and the actuation of the audible signal device is deferred until the operator responds to the call. The line-indicator is coin-controlled, and the audible signal while also coin-controlled, is deferred until the central operator responds. The central operator can thereby detect a call obtained through operation of the line-indicator by fraudulent means. 110

After having ascertained the connection desired, by the depositor of the coin, the central operator will ascertain in usual manner whether or not the desired connection can be 115 120 125 130

obtained. If the line wherewith communication is desired, is not busy, the central operator gives the subscriber the desired connection. It will be observed that no action 5 or further conversation is necessary on the part of the central operator, because the deposited coin already beyond control of the depositor, will remain in the distributor until displaced during the initial part of the next 10 succeeding shift of the coin-carrier, when it will be displaced into the coin-drawer. If the desired service or connection cannot be given, the operator shifts switch 66 in the cord-circuit L, to cause generator current to 15 pass from generator 64, through tip of the inserted plug, contact-spring i of the spring-jack, branch 55 of the line, switch hook 57, contact-spring 71, conductor 70, and electromagnet G to ground at 72. Energization of 20 said magnet will cause armature e to be attracted, shift distributor E forwardly, and the deposited coin will be displaced from stop 44, into cup 9, and be refunded. Such return of the coin will be a notification to the 25 depositor that the desired connection cannot be obtained.

From the operation and mechanism defined, it will be seen that the central operator is not obliged to perform any other function 30 than making the usual connection, unless a coin is to be refunded. In other words, the duties of the central operator are precisely the same as those necessary with stations wherefor a periodical rental is paid, unless 35 the service cannot be given, in which event instead of informing the subscriber to such effect, the operator refunds the coin. This resultant advantage is a very important one, because in exchanges where both toll-sta- 40 tions and leased stations are used, the operator will not become confused in her duties and moreover, the displacement of the coins received in payment is not effected by the operator but is automatically effected during 45 the succeeding operation of the toll-receiver. The improved toll-receiver provides a device wherein no special operation of either depositor or central operator is necessary to displace the coin into the cash-drawer, and 50 consequently the functions of the operator are materially lessened, which results in improved service. A further advantage of the improved device is that the necessity of utilizing the deposited coin as a conductor or 55 of operating contact-springs by the gravity of the coin itself, are entirely avoided, the coin is positively shifted to effect the movement of the switch which completes the signal circuit wherein the line-relay is included. 60 The mechanism for locking or holding the switch and audible signal-device until the central operator responds to the call, assures response from the exchange before the audible-signal device is operated and thereby 65 the line is promptly freed of grounded con-

nnections. Another important advantage is that the apparatus provides a system wherein the line-signal is coin-controlled, and a coin-controlled audible signal is deferred until the operator responds, and furthermore, the audible signal confirms the actuation of the line-relay so the central operator can detect the fraudulent operation of the line-signal. The toll-receiver is simple in construction and positive in its operation. 70

While the device is shown as adapted to receive coins, it is obvious that any toll representing check or token can be used, and the word "coin" as used herein is to be understood as including any toll-representing 75 check or token. The term "coin-distributer", as used in the claims is not to be understood as defining the particular construction shown and described, unless the construction is specifically defined therein. 80

The particular arrangement and construction may be varied within wide limits by those skilled in the art, and the novel features may be employed severally without adoption of the invention in entirety, and without departing from the spirit of the invention. 85

Having thus described my invention, what I claim as new and desire to secure by Letters Patent is:—

1. In a telephone toll apparatus, the combination with means for disposing of a coin in a plurality of directions, means for directing said coin in one of said directions by the insertion of another coin, and means operated from the exchange for disposing of said coin in another of said directions. 95

2. In a telephone toll apparatus, the combination with means for disposing of a coin in a plurality of directions, of means operable by the depositor for directing said coin in one of said directions upon the insertion of another coin, and means operated from the exchange for disposing of said first coin in another of said directions. 105

3. In a telephone toll apparatus, the combination with means for disposing of a coin in a plurality of directions, means operable by another inserted coin for displacing said first coin in one of said directions, and means for shifting said second coin to operate said displacing means. 110

4. In a telephone toll apparatus, the combination of means for refunding a coin operable by the exchange operator, means for retaining a previously deposited coin when another coin is deposited, and means for shifting the deposited coin to operate the retaining means. 120

5. In telephone-toll apparatus, the combination of coin-distributing-means for causing a coin to be refunded or retained, means for causing a deposited coin to be refunded and operable by the exchange operator, and means for operating the distributing-means 125

130

to retain a previously deposited coin when another coin is deposited.

6. In a telephone toll apparatus, the combination with means for disposing of a coin in a plurality of directions, means for directing said coin in one of said directions by the insertion of another coin, and electro-magnetic means controlled from the exchange for disposing of said coin in another of said 10 directions.

7. In telephone-toll apparatus, the combination of coin-refunding means, an electro-magnet for operating the refunding means, means for energizing said electro-magnet 15 under control of the exchange operator, means for retaining a previously deposited coin when another coin is deposited, and means operable by the depositor for shifting a deposited coin to operate the retaining 20 means.

8. In toll-receiving apparatus for telephones, the combination of coin-refunding-means, means for causing a deposited coin to be retained, a movable coin-carrier for 25 shifting a coin to cause a previously deposited coin to be retained, and electro-magnetic means for operating the refunding means.

9. In toll-receiving apparatus for telephone lines, a coin-distributer, a movable coin-carrier for shifting a coin, means for shifting the distributer in one direction when a coin is shifted by the carrier, a support for 30 holding a coin in the distributer, a refunding passage and a retaining passage at the sides of said support, an electro-magnet for shifting the distributer in the other direction, and means for energizing the magnet.

10. The combination with a telephone line 40 of coin-refunding-means, means for causing displacement of a coin so it will be retained, a signal-circuit, a switch for controlling passage of current over said circuit, and means for shifting a coin to operate the switch and 45 to cause displacement of a previously deposited coin so it will be retained.

11. The combination with a telephone line 50 of coin-refunding-means, means for causing displacement of coin so it will be retained, a signal-circuit, a switch for controlling passage of current over said circuit, means for shifting a coin to operate the switch and to cause displacement of a coin so it will be retained, and electro-magnetic means for operating 55 the refunding-means.

12. The combination with a telephone line 60 of a signal-circuit, coin-refunding means, means for causing displacement of a coin so it will be retained, a coin-controlled switch for controlling the signal-circuit, means operable by the exchange operator for operating the refunding means, and means for causing a deposited coin to operate the coin-displacing-means and said switch.

13. In toll-receiving apparatus for telephones, the combination of a swinging coin-carrier for holding and shifting a coin, a signal-circuit, a switch for controlling passage of current over said circuit, a dog for preventing retraction of a coin held in said 70 carrier, and means for shifting said switch when a coin is shifted by said carrier.

14. In toll-apparatus for telephones, the combination of a swinging coin-carrier for shifting a deposited coin, a signal-circuit, a switch for controlling passage of current over 75 said circuit, a dog in the path of travel of a coin in the carrier for preventing retraction of the carrier, and means for causing the coin in the carrier to shift the switch. 80

15. In toll apparatus for telephones, the combination of a signal, a switch for controlling the operation of said signal, a movable coin-carrier, an arm extending in the path of travel of a coin in said carrier and for shifting the switch when a coin is shifted by the carrier, and means for holding the switch in 85 operated position.

16. In toll-apparatus for telephones, the combination of coin-shifting-means operable 90 by the depositor, a signal, a switch for controlling the operation of said signal, means for holding said switch in shifted position when a coin is shifted by the shifting-means, and electro-magnetic means for operating 95 the holding means to release the switch.

17. In toll-apparatus for telephones, the combination of a swinging coin-carrier, a signal, a switch controlling the operation of the signal, an arm extending into the path of 100 travel of a coin in the carrier and for shifting said switch, means for holding said switch in shifted position, and means for releasing said switch from said holding means.

18. In toll-apparatus for telephones, the combination of a switch, a signal controlled 105 by said switch, means for causing the coin to shift said switch in one direction, means for locking said switch to retain it in shifted position, and means operable by the exchange-operator for releasing the switch. 110

19. In toll-apparatus for telephones, the combination of a switch, a signal controlled by said switch, means for shifting a coin to shift said switch, means for locking said 115 switch to retain it in one position, an electro-magnet for releasing the switch, and means for energizing the electro-magnet.

20. In toll-apparatus for telephones, the combination of a switch, a signal controlled 120 by said switch, means for positively shifting a coin to shift said switch, means for locking said switch in shifted position, and means operable by the exchange-operator for releasing the switch. 125

21. In toll-apparatus for telephones, the combination of a switch, a signal controlled by said switch, means for positively shifting

a coin to shift said switch, means for locking the switch in shifted position and electro-magnetic means for releasing the switch.

22. In toll-apparatus for telephones, the 5 combination of a switch, means for shifting a coin to shift said switch in one direction, means for locking the switch to retain it in one position, an electro-magnet for releasing the switch, means for energizing the electro- 10 magnet, coin-distributing-means, and means for operating the distributing-means so a previously deposited coin will be retained when a coin is shifted to operate said switch.

23. In toll-apparatus for telephones, the 15 combination of a switch, a coin-carrier, coin-distributing-means for directing a coin into a refunding path or a retaining path, means for operating the distributing means to displace a coin into the retaining path when a coin is 20 deposited, means for shifting said switch when a coin is deposited, locking means for said switch, an electro-magnet for releasing the switch, and means for energizing the electro-magnet.

24. The combination with a telephone line extending from the sub-station to an exchange, of a line-signal, means for disposing of a coin in a plurality of directions, means for directing said coin in one of said directions by the insertion of another coin, means operated from the exchange for disposing of said coin in another of said directions, and means for operating the line-signal when a coin is inserted.

25. The combination with a telephone line extending from a sub-station to an exchange, of a line signal, means for disposing of a coin in a plurality of directions, means for directing said coin in one of said directions by the insertion of another coin, an electro-magnet operated from the exchange station for disposing of said coin in another of said directions and means for operating the line-signal when a coin is inserted.

26. The combination with a telephone line extending from a sub-station to an exchange, of a coin-controlled line-signal, coin-refunding-means, means for causing displacement of a deposited coin so it will be retained, 50 means for shifting a coin to operate the displacing means to cause a previously deposited coin to be retained, and means operable by the exchange-operator for operating the refunding-means.

27. The combination with a telephone line extending from a sub-station to an exchange, of a coin-controlled line-signal, coin-refunding-means, means for causing displacement of a deposited coin so it will be retained, 60 means for shifting a coin to operate the displacing means to cause a previously deposited coin to be retained, and electro-magnetic means for operating the refunding means.

28. The combination with a telephone line 65 extending from a sub-station to an ex-

change, of a line-signal, a signal-circuit, a switch for controlling said circuit, coin-refunding-means, means for causing displacement of a deposited coin so it will be retained, means for causing a coin to operate the displacing means so a previously deposited coin held thereby will be retained and for causing the coin to operate said switch to cause the operation of the line signal, and means under the control of the exchange-operator for 75 operating the refunding means.

29. The combination with a telephone line extending from a sub-station to an exchange, of a line-signal, a signal-circuit, a switch for controlling said circuit, coin-refunding-means, means for causing displacement of a deposited coin so it will be retained, means for causing a coin to operate the displacing means so a previously deposited coin held thereby will be retained and for causing the coin to operate said switch to cause the operation of the line-signal, and electro-magnetic means for operating the refunding means.

30. The combination with a telephone line extending from a sub-station to an exchange, of a line-signal, a signal-circuit, a switch for controlling said circuit, coin-refunding means, means for causing displacement of a deposited coin so it will be retained, and means for shifting a coin to operate the displacing means so a previously deposited coin held thereby will be retained and for shifting the coin to operate said switch to cause the operation of the line-signal.

31. The combination with a telephone line extending between a sub-station and an exchange, of an electric circuit normally open at the sub-station, a line-signal at the exchange, a coin-controlled switch for controlling passage of current over said circuit to control actuation of the line-signal, means for shifting said switch when a coin is deposited to cause actuation of the line-signal, and means for holding the switch in position to cause the actuation of the line-signal, the holding means being independent of the coin and of said circuit.

32. The combination with a telephone line extending between a sub-station and an exchange, of an electric circuit normally open at the sub-station, a line-signal at the exchange, coin-refunding means under the control of the exchange-operator, a coin-controlled switch for controlling passage of current over said circuit to control actuation of the line signal, means for shifting said switch when a coin is deposited to cause actuation of the line-signal, and means for holding the switch in position to cause the actuation of the line-signal, the holding means being independent of the coin and of said circuit.

33. The combination with a telephone line extending between a sub-station and an exchange, a line-signal at the exchange, a signal

- circuit, a coin-controlled switch at the sub-station for controlling the line signal, means for causing a coin to shift said switch to cause the operation of the line signal, 5 means for restoring said switch when the exchange-operator inserts a plug into the switchboard in response to a call, and coin-refunding means controlled by the exchange-operator.
- 10 34. The combination with a telephone line extending between a sub-station and an exchange, of a signal-circuit normally open at the sub-station, a line-signal at the exchange, a coin-operated switch at the sub-station for 15 controlling passage of current over said circuit, means for directing a coin to shift said switch, and means for shifting said switch to open said circuit at the sub-station when the exchange-operator inserts a plug into the 20 switch-board in response to a call.
35. The combination with a telephone line extending between a sub-station and an exchange, of a signal-circuit normally open at the sub-station, a line-signal at the exchange, 25 a coin-operated switch at the sub-station for controlling passage of current over said circuit, means for directing a coin to shift said switch, means for shifting said switch to open said circuit at the sub-station when the exchange-operator inserts a plug into the 30 switch-board in response to a call, and coin-refunding means under the control of the exchange operator.
36. The combination with a telephone line 35 extending between a sub-station and an exchange, of a signal-circuit normally open at the sub-station, a coin-controlled switch at the sub-station for controlling passage of current over said circuit, means for holding said 40 switch in one position and an electro-magnet for causing said switch to be shifted, and means for energizing the magnet to shift the switch when the exchange operator inserts a plug into the switchboard in response to a 45 call.
37. The combination with a telephone line 50 extending between a sub-station and an exchange, of a signal-circuit normally open at the sub-station, a coin-controlled switch at the sub-station for controlling passage of current over said circuit, means for holding said switch in one position and an electro-magnet for causing said switch to be shifted, means 55 for energizing the magnet to shift the switch when the exchange-operator inserts a plug into the switch-board in response to a call, and coin-refunding-means under control of the exchange operator.
38. The combination with a telephone line 60 extending between a sub-station and an exchange, of a signal circuit grounded and normally open at the sub-station, a line-signal at the exchange, a coin - controlled switch for controlling said circuit, means for 65 holding said switch in position to close said

circuit at the substation, an electro-magnet for causing said switch to open said circuit, and means for energizing said magnet when the operator inserts a plug into the switch-board in response to a call.

70 39. The combination with a telephone line extending between a sub-station and an exchange, of a signal-circuit grounded and normally open at the sub-station, a line-signal at the exchange, a coin-controlled switch for controlling said circuit, means for holding said switch in position to close said circuit at the sub-station, an electro-magnet for causing said switch to open said circuit, means for energizing said magnet when the operator 75 inserts a plug into the switch-board in response to a call, and coin-refunding means under control of the exchange operator.

80 40. The combination with a telephone line extending between a sub-station and an exchange, of an electric-circuit normally open at the sub-station, a line-signal at the exchange, means for shifting a coin, a switch for controlling the line - signal, means for shifting said switch when a coin is shifted by 85 the shifting means, means for holding said switch in position to close the signal-circuit at the sub-station, an electro-magnet for causing said switch to be shifted to open said circuit, and suitable means and connections 90 for energizing said electro-magnet to cause the switch to open the circuit when the exchange operator inserts a plug into the 95 switch-board in response to a call.

100 41. The combination with a telephone line extending between a sub-station and an exchange, of a signal-circuit normally open at the sub-station, a line-signal at the exchange, means for shifting a coin, a switch for controlling the line-signal, means for shifting 105 said switch when a coin is shifted by the shifting means, means for holding said switch in position to close the signal-circuit at the sub-station, an electro-magnet for causing said switch to be shifted to open said 110 circuit, suitable means and connections for energizing said electro-magnet to cause the switch to open the circuit when the exchange operator inserts a plug into the switch-board in response to a call, and coin-refunding-means under control of the exchange operator.

115 42. The combination with a telephone line extending between a sub-station and an exchange, of an electric circuit normally open 120 at the sub-station, a line signal at the central office, a coin-controlled switch at the sub-station for controlling passage of current over said circuit, means for locking said switch in position to close said circuit, and means for releasing said switch to open said circuit when the exchange-operator inserts a plug into the switchboard in response to a call.

125 43. The combination with a telephone line 130

extending between a sub-station and an exchange, of an electric circuit normally open at the sub-station, a line-signal at the exchange, a coin-controlled switch at the sub-
5 station for controlling passage of current over said circuit, means for locking said switch in position to close said circuit, an electro-magnet for releasing said switch, and means for energizing said electro magnet to
10 cause said switch to be released, and to open said switch when the operator inserts a plug into the switch-board in response to a call.

44. The combination with a telephone line extending between a sub-station and an exchange, of an electric circuit normally open at the sub-station, a line-signal at the exchange, a coin-controlled switch at the sub-station for controlling passage of current over said circuit, means for locking said
15 switch in position to close said circuit, an electro-magnet for releasing said switch, means for energizing said electro-magnet to cause said switch to be released and to open said switch when the operator inserts a plug
20 into the switchboard in response to a call, and coin-refunding means under control of the exchange-operator.

45. The combination with a telephone line extending between a sub-station and an exchange, of a signal-circuit, a line-signal at the exchange, a coin-controlled switch at the sub-station for controlling the line signal, coin-refunding means, means for causing displacement of a coin so it will be retained,
30 means for holding the switch in position to cause the operation of the line-signal, means for causing a coin to operate said switch to cause the operation of the line-signal, and means for operating the coin displacing
35 means when said switch is operated, and electro-magnetic means for releasing said switch.

46. The combination with a telephone line extending between a sub-station and an exchange, of a signal-circuit, a line-signal at the exchange, a coin-controlled switch at the sub-station for controlling the line signal, coin-refunding means, means for causing displacement of a coin so it will be retained,
45 means for holding the switch in position to cause the operation of the line-signal, means for causing a coin to operate said switch to cause the operation of the line-signal, means for operating the coin displacing means when
50 said switch is operated, and electro-magnetic means for releasing said switch, and coin-refunding means under control of the exchange-operator.

47. The combination with a telephone line extending between a sub-station and an exchange, of a signal-circuit, a line-signal at the exchange, a coin controlled switch at the sub-station, coin-refunding means, switch holding means, an electro-magnet for operating the switch holding means to release the

switch, an electro-magnet for operating the coin-refunding means, a conductor in which the magnet for the refunding-means is included, said conductor being connected to the telephone line and normally open at the switch hook of the sub-station, said electro-magnets being of different resistances, and means under control of the exchange operator for energizing said electro-magnets.

48. The combination with a telephone line extending between a sub-station and an exchange, of a signal-circuit, a line-signal at the exchange, a coin-controlled switch at the sub-station, coin-refunding means, means for causing displacement of a coin so it will be retained when another coin is deposited, means for shifting said switch when a coin is deposited to cause the actuation of the line signal, means for holding the switch in shifted position, an electro-magnet for causing said switch to be released, an electro-magnet for operating the refunding means, a conductor connected to the telephone line and in which the helix of the magnet for the refunding means is included, said conductor being normally open at the switch-hook of the sub-station, said electro-magnets being of different resistances, and means for energizing said electro-magnets.

49. The combination with a telephone line connecting a sub-station and an exchange, a signal circuit, a line-signal at the exchange, a coin-controlled switch at the sub-station for controlling the line-signal, a coin-controlled device for producing an audible-signal at the sub-station, and means operable from the exchange for causing the operation of the audible-signal device to confirm the operation of the line-signal switch by a coin.

50. The combination with a telephone line connecting a sub-station and an exchange, a signal-circuit, a line-signal at the exchange, a coin-controlled switch for the line signal, a device at the sub-station for producing an audible signal and comprising an actuating part, means for causing a coin to shift said actuating part when said switch is shifted by a coin to actuate the line-signal, and means for causing the operation of the audible-signal device to confirm the operation of the switch by a coin.

51. The combination with a telephone line connecting a sub-station and an exchange, a signal-circuit, a line-signal at the exchange, a coin-controlled switch at the sub-station for controlling the line-signal, a coin-controlled device for producing an audible-signal at the sub-station, and electro-magnetic means for causing the operation of the audible-signal device to confirm the operation of the line-signal by the switch.

52. The combination with a telephone line connecting a sub-station and an exchange, a signal-circuit, a line-signal at the exchange, a coin-controlled switch for the line-signal,

a device at the sub-station for producing an audible-signal and comprising an actuating part, means for causing a coin to shift said actuating part when said switch is shifted by a coin to actuate the line-signal, electro-magnetic means for causing the operation of the audible-signal device to confirm the operation of the switch by a coin.

53. The combination with a telephone line connecting a sub-station and an exchange, of a signal-circuit, a line-signal at the exchange, coin-controlled means at the sub-station for causing the passage of current over said circuit, a coin-controlled device at the sub-station for producing an audible signal, and means for causing the actuation of the audible-signal device when the operator inserts a plug into the switchboard to respond to a call.

54. The combination with a telephone line connecting a sub-station and an exchange, of a signal-circuit, a line-signal, a switch at the sub-station for causing the operation of said signal, a device at the sub-station for producing an audible-signal and comprising a movable part, means for shifting a coin to shift said part and said switch, means for holding said movable part in shifted position, and electro-magnetic means for releasing said part.

55. The combination with a telephone line connecting a sub-station and an exchange, of a signal-circuit, a line-signal, a switch at the sub-station for causing the operation of said

signal, a device at the sub-station for producing an audible-signal and comprising a movable part, means for shifting a coin to shift said part and said switch, means for holding said movable part in shifted position, and means for causing said part to actuate the audible-signal-device when the operator inserts a plug into the switch-board in response to a call.

56. In toll-receiving apparatus, the combination of a switch, a device for producing an audible signal, coin distributing means, mechanism for causing the operation of said switch and said distributing means and for operating said device, and means for causing a coin to operate said mechanism.

57. A toll-receiving apparatus comprising the combination of a switch, a device for producing an audible signal, coin-distributing means, and mechanism for shifting a coin to cause the operation of said switch and said distributing means and to actuate said device.

58. In a toll collector, means for holding a toll piece in suspense, electro-magnetic means for controlling the return of said toll piece to the depositor, and a device controlled by a subsequently deposited toll piece for cashing said first mentioned toll piece.
